CABLE AND SEISMOMETER SUPERSTRUCTURE FOR PICKUP TRUCKS

Clifford D. Dransfield and Darvin D. Shields, Dallas,
and Oswald Paxton, Plano, Tex., assignors to Atlantic
Richfield Company, New York, N.Y.

Filed June 11, 1969, Ser. No. 17,658

Term of patent 14 years

Int. Cl. D12—16

U.S. Cl. D14—3

Fig. 1

Fig. 2

Fig. 3

*Fig. 4**Fig. 5*FIG. 1 is a side elevational view of a cable and seismometer superstructure for pickup truck embodying our design, mounted on a pickup truck;

FIG. 2 is a rear elevational view thereof;

FIG. 3 is a rear perspective view thereof with the back gate of the superstructure removed, showing inside the rear compartment;

FIG. 4 is a top plan view thereof, showing that the front compartment of the superstructure is open at the top; and

FIG. 5 is a perspective view of the superstructure with one of the front side gates removed, showing inside the front compartment.

The portion of the drawing shown in dotted lines is not a part of the design and is included for illustrative purposes only.

We claim:

The ornamental design for a cable and seismometer superstructure for pickup trucks, substantially as shown and described.
